UNITED STATES PATENT OFFICE.

ALBERT H. TAYLOR, OF WASHINGTON, DISTRICT OF COLUMBIA, ASSIGNOR TO WIRED RADIO, INC., OF NEW YORK, N. Y., A CORPORATION OF DELAWARE.

AMPLIFICATION SYSTEM.

Application filed August 19, 1927. Serial No. 214,073.

My invention relates broadly to high power electron tube transmitter circuits and more particularly to a system of power transfer for transmitter circuits.

5 One of the objects of my invention is to provide a circuit arrangement for a high frequency oscillator and power amplifier in a signal transmitter system for stabilizing the operation of the tube circuits and effecting a transfer of high frequency energy at 10 high power.

Another object of my invention is to provide a circuit arrangement for a piezo electric crystal controlled transmitter wherein a 15 system of series plate tuning is provided in the power amplifier system for balancing the operation of the circuit and preventing violent self-oscillations which are liable to kick back into the crystal circuit and 20 impair the operation of the crystal.

Still another object of my invention resides in the arrangement of series plate tuning for the electron tube circuits of a high power transmitter, as described more fully 25 in the specification hereinafter following by reference to the accompanying drawings wherein:

Figure 1 shows a piezo electric crystal controlled oscillator and power amplifier 30 circuit showing one system for balancing the operation of the circuits; Figs. 2 and 3 illustrate diagrammatically the electrical elements in the circuit of Fig. 1; Fig. 4 illustrates the series plate tuning arrangement of 35 my invention in an electron tube transmitter system; and Figs. 5 and 6 diagrammatically illustrate the elements included in the circuit of Fig. 4.

Figure 1 shows a master oscillator power 40 amplifier circuit with a balance between the power amplifier 1 and the master oscillator 2. The particular circuit illustrated uses a parallel high voltage feed to plate and piezo electric control. Various methods of keying 45 the circuit may be provided.

The master oscillator includes the piezo electric crystal element 10 connected in the input circuit of the master oscillator 2, with a suitable radio frequency choke 11 arranged 50 with respect thereto for securing operation of the oscillator with substantially no load upon the piezo electric crystal element 10. The output circuit of the oscillator 2 includes

the inductance system 12 having a portion thereof tuned by means of condenser 14. A 55 blocking condenser 15 is arranged in circuit with inductance 12, permitting the passage of high frequency oscillations through the inductance 12, while preventing the passage 60 of direct current from the excitation source of the plate circuit. The radio frequency choke coil 16 prevents high frequency currents from reaching the source of direct current potential. The cathode of the oscillator 2 is heated from a suitable source represented at 17. By adjusting the tap 18 on inductance 12 and controlling the position of condenser 14, the circuits can be adjusted to the desired condition for sustaining oscillations having the frequency of piezo electric crystal element 10. The power amplifier system 1 has its input circuit connected with the output circuit of the master oscillator by means of a tap 20 on inductance 12 and a 65 connection 21 along the inductance 12. The power amplifier tube 1 and its grid electrode are biased from source 22 through radio frequency choke coil 23. A blocking condenser 25 is connected with the grid circuit of the power amplifier 1. The portion of inductance 12 indicated at 26 operates in conjunction with the adjustable connector 27 connected at point 28 in the output circuit of power 70 amplifier 1 for balancing the operation of the power amplifier. The high potential 75 source for exciting the power amplifier 1 is obtained through choke coil 29. The plate circuit or inductance 3 may have a portion thereof shunted by condenser 4. Condenser 30 is placed in series in the output circuit 80 with the inductance 3. I have illustrated connections from the inductance 3 to a succeeding stage of amplification or to a load circuit, such as an antenna and ground or 85 counter-noise system.

Fig. 2 shows a schematic diagram of the power amplifier circuit without the balance and without any load such as an antenna, or second amplifier on the plate circuit. It will be seen that this circuit shown in Fig. 2 is 100 not one with a single resonance point but is complicated by the fact that there is a capacity in parallel with a portion of the plate circuit inductance. For the case of low frequencies where the inductance becomes ultimately large and the parallel plate tuning 105

condenser which shunts part of this inductance is also large, the capacity of the plate itself indicated by C_p at points A—D can be neglected and the circuit becomes a simple 5 circuit with only one resonance point. In other words, the portion of the inductance together with the stopping condensers and the connection to the plate, is to be considered as an aperiodic circuit, the capacity C_p 10 being so small in most tubes that at long waves or low frequencies it is considered as a safe degree of approximation, as being negligible as far as its influence on the circuit is concerned. In considering small 15 variations, however, this approximation naturally cannot be made. When the circuit is considered with the addition of the balance 20—27 and by an antenna load having constants L, R, C, as shown in the schematic 25 diagram, Fig. 3, it is not unnecessarily complicated at low frequencies, particularly if the balance condenser 27 is relatively small and the coupling to the antenna system is relatively loose. But, as pointed out, Fig. 2 30 becomes a complicated circuit as soon as high frequencies are approached where the inductances become very small and the high capacity C_p carries a relatively large value 35 of radio frequency current. In such cases this plate capacity has a very marked influence on the tuning and the circuit is complicated by having more than one tuning point. This complication is, of course, particularly aggravated when the balance 40 arrangement is put in and the antenna coupled to the transmitter. It is to be understood that in the place of the antenna a second amplifier tube can be coupled in, either with or without balance. The driving E. M. F. in the schematic diagram of Figs. 2 and 3 45 must be considered as being applied between the point A and D.

Fig. 4 shows the application of my improved modified series tuning system to a 45 transmission circuit wherein the paralleling of a portion of the plate circuit inductance 50 by a tuned condenser 4 (Fig. 1) is avoided, but where the plate filament capacity C_p is augmented by a preferably adjustable condenser placed immediately in parallel with it inside the condenser 6. The advantage of 55 this circuit arrangement, which I have termed the modified series plate tuning, consists in the addition of this condenser 6, thus permitting an adjustment of external and internal impedance when it comes to transferring the plate circuit energy to an antenna, another amplifier, or any form of load.

Fig. 5 shows the schematic diagram of a 60 plate circuit thus tuned, but without antenna or other load, and without balance. The plate circuit capacity C_p is augmented and can be represented by a single capacity between points A and D, at which the driving

E. M. F. is applied. The blocking condenser 30 is variable for even adjustment but may be made fixed and tuning carried on by variation of inductance. The circuit becomes a very simple series circuit with one degree 70 of freedom. As this circuit is complicated by the addition of the balance circuit and load circuit as shown in Fig. 6, it now has more than one degree of freedom, but if the balance condenser is kept fairly small 75 and the coupling series loose, it does approximate the very simple condition shown in Fig. 5, and in any case, it is a vastly simpler circuit theoretically than the circuit shown in Fig. 3. Only now, it is found that 80 especially at the higher frequencies, say 6000 kcs. and upwards, the circuits represented by Figs. 1-2-3 are extremely difficult to handle without getting into various troubles due to erratic tuning, self-oscillations of amplifiers, excessive plate currents, impurity of wave form and other difficulties. On the other hand, circuits shown in 85 Figs. 4-5-6 with the modified plate tuning are applicable for a wide range of tube types 90 and have demonstrated themselves to be of remarkably good efficiency and free from practically all of the difficulties previously mentioned. This particular circuit has been tried with 50-watt thoriated filament tubes, 95 250-watt thoriated filament tubes, and 1 k. w. thoriated filament tube and with a special tube for higher frequencies which is not a standard tube. They have also been tried 100 with a water cooled tube with excellent results from the point of view of output, ease of carrying out the balance and stability.

It must be specifically noted that the one kilowatt air cooled tube, known as General Electric type 851, and known in the Naval 105 Service as CG 2172, has heretofore given an immense amount of trouble in all radio operations. The United States Naval Research Laboratory at Bellevue, Anacostia, D. C., has, over a period of two and one-half years, been endeavoring to get this type 110 of tube to work properly as a power amplifier at frequencies higher than 3000 kcs. with practically no success at all higher than 4000 kcs. and with very unstable adjustment. This particular tube is a low voltage 115 tube; normal operating voltage being 2000 volts on the plate. This means, therefore, that it has to carry a high plate current in the neighborhood of one ampere and that the internal inter-electrode capacities are very large. This tremendously aggravates the bad condition explained when circuits 120 similar to circuits shown in Figs. 1-2-3 are used, but, on the other hand, with the circuits shown in Figs. 4-5-6 this tube, which for more than two years has defied all efforts to produce satisfactory power amplifier 125 action at high frequencies, operates in a highly satisfactory manner. The position- 130

ing of the condenser 6 in the circuit permits a considerable variation in the plate circuit tuning inductance and gives the circuit the

5 proper $\frac{L}{C}$ ratio to make its operation efficient

as a power amplifier when its energy is fed over by any means of coupling into any form of load.

10 The power amplifier system operates efficiently with the piezo electric crystal control system of my invention by reason of the prevention of violent self-oscillations in the circuits which are liable to kick-back into 15 the crystal circuit and destroy the crystal.

The arrangement of the circuits has been found to be very practical in high power transmitter operation, and while I have described a preferred arrangement of circuit, 20 I desire that it be understood that modifications may be made and that no limitations upon my invention are intended other than are imposed by the scope of the appended claims.

25 What I claim as new and desire to secure by Letters Patent of the United States is as follows:

1. In an electron tube transmission system a piezo electric crystal controlled oscillator 30 circuit, a power amplifier connected with said oscillator circuit, said power amplifier including input and output circuits, a circuit including inductance, a condenser in series therewith; a condenser in parallel 35 with said inductance and said aforementioned condenser, connections between said output circuit and said last mentioned condenser for the transfer of power to said inductance while preventing the kick-back of 40 energy into said piezo electric crystal controlled oscillator circuit.

2. An electron tube transmitter circuit comprising a piezo electric crystal controlled oscillator, a power amplifier having an input 45 circuit and an output circuit, connections between said input circuit and said piezo electric crystal controlled oscillator, a circuit including an inductance, a condenser in series with said inductance, and a condenser 50 connected between one side of said afore-

mentioned condenser and a point in said inductance, said last mentioned condenser being disposed in parallel with the output circuit of said power amplifier for the transfer of high frequency energy from said power amplifier to said inductance while preventing the kick-back of energy upon 55 said piezo electric crystal controlled oscillator.

3. An electron tube transmission system 60 comprising a piezo electric crystal controlled oscillator, a power amplifier stage constituted by an electron tube having grid, filament and plate electrodes, an input circuit extending between said grid and filament 65 electrodes and coupled with the output circuit of said piezo electric crystal controlled oscillator, an output circuit extending between the plate and filament electrodes of said power amplifier stage, said output circuit including a connection to an inductance from the plate electrode through a condenser, and a connection from a point in said inductance to said filament electrode, and a condenser connected in shunt with said plate 70 and filament electrodes and across a series circuit constituted by said first mentioned condenser and inductance for facilitating the transfer of power from said power amplifier stage while preventing the kick-back 75 of energy upon said piezo electric crystal controlled oscillator.

4. An electron tube transmitter system 80 comprising a piezo electric crystal controlled oscillator, a power amplifier constituted by 85 an electron tube having grid, filament and plate electrodes, an input circuit connected between said grid and filament electrodes and coupled with said piezo electric crystal controlled oscillator, an output circuit extending between said plate and filament electrodes, said output circuit being shunted by means of a condenser, and connections extending from opposite sides of said condenser including a condenser and inductance in 90 series for facilitating the transfer of power from said power amplifier while preventing the kick-back of energy upon said piezo electric crystal controlled oscillator.

ALBERT H. TAYLOR.
